UNITED STATES PATENT OFFICE.

JOHN SHERMAN MCCHESNEY, OF CHICAGO, ILLINOIS, ASSIGNOR, BY MESNE ASSIGNMENTS, TO THE GERRARD COMPANY, INC., OF SAN FRANCISCO, CALIFORNIA, A CORPORATION OF DELAWARE.

WIRE-TYING MACHINE.

Application filed October 28, 1924. Serial No. 746,280.

This invention is a machine for tensioning a tie wire tightly around a package of one character or another, and for uniting the end portions of said tie wire by a simple operation, the machine functioning to perform the tensioning and tying operations rapidly and effectively so as to minimize the labor and skill required for the manual application of the wire to the package.

10 According to the invention, the machine embodies an appropriate frame provided with a throat for the reception of overlapping portions of a looped tie wire, a lever-controlled tension means including a plurality of rotatable heads to which the respective end portions of the tie wire are adapted to be connected, a lever-controlled tie joining means whereby the ends of the tie are united while said tie is under tension, and tie-cutting

20 means for severing the tie adjacent the splice or knot subsequently to the tying operation, whereby the tie-cutting means operates to disconnect the machine from the applied wire tie so as to enable the operator to shove the

25 machine away from the applied tie.

In this apparatus, the tension means embodies a plurality of heads rotatable with a shaft, one of said heads being provided with a ratchet. The tension lever is connected or 30 fitted loosely to the shaft, in order that said lever may be returned to a position in which it is held conveniently by hand for steadily retaining the machine with reference to the looped tie when the other lever is actuated 35 for the performance of the tying operation. Said tension lever co-operates with the ratchet formed tension head for imparting rotative movement thereto when the lever is moved in one direction, and to this end said 40 tension lever is provided with a dog or pawl adapted to engage with one of a series of teeth on said ratchet, whereby the tension lever may be moved in one direction for turning the ratchet, the shaft and the two tension heads in a manner to rotate said tension heads 45 simultaneously, and thus adapt the same for pulling on the tie wire in opposite directions and thereby place said tie wire quickly under tension, the amount of strain or pull put on the tie wire being within the discretion of 50 the operator.

The ratchet formed tension head is restrained from rotative movement in one direction by a check pawl or dog which co-

operates with one of the ratchet teeth, said 55 pawl or dog being independent of the feed pawl carried by the tension lever, it being understood that in my invention two pawls are employed, both of which co-operate with the one ratchet on one rotatable tension head. 60 One pawl, i. e. the feed pawl on the tension lever, acts to impart a rotative step feed to the ratchet formed tension head, whereas the other pawl, i. e. the check pawl, acts to restrain the ratchet formed tension head from 65 rotative movement in an opposite direction to that which is given by the feed pawl and tension lever, said check pawl operating to preclude rotation of the ratchet formed tension head under the strain or pull of the tie wire 70 when the latter is tensioned around the package.

My invention consists, further, of a double cutting mechanism the parts of which are coordinated for operation by a forward movement of the tie-joining lever and the cutters of which mechanism are positioned to sever surplus wire from the end portions of the looped tie and to effect said severance of the tie close to the respective ends of the knot or 75 splice uniting the tie to produce a closed loop or band around the package. The cutters are of simple and durable construction, readily blanked from steel and requiring the least amount of labor for their economical 80 production, one of said cutters being so fashioned that it is free from contact with its actuating stud on the tie twisting lever during 85 a certain period in the forward swing of said lever.

My invention includes, also, a shock absorbing device carried by the tie-twisting lever and adapted to be seated upon a stationary part of the frame as said lever approaches the limit of its movement in one direction, said 90 shock absorbing means being effective in cushioning the swing of the lever when swung rapidly forward for operating the twister and the double cutter, and said shock absorbing means functioning, also, in returning 100 said twister operating lever to a position which will turn the twister pinion into a position for the slot in said twister pinion to register with the throat of the machine frame whereby the machine as a whole may be displaced with respect to the knot or splice and to the looped tie without hindrance from the 105 twister pinion.

Other functions and advantages of the invention will appear from the following description taken in connection with the drawings, wherein—

5 Figure 1 is a perspective view of my wire tying machine in an operative position upon a package for applying a looped tie wire under tension around said package.

10 Figure 2 is a horizontal sectional plan view through the machine, the tie wire being omitted and the plane of section being centrally through the single shaft or spindle.

15 Figure 3 is a vertical cross section on the irregular line 3—3 of Figure 2.

20 Figure 4 is a vertical cross section on the line 4—4 of Figure 2, illustrating one cutter of the double cutting mechanism.

25 Figure 5 is a vertical cross section on the line 5—5 of Figure 2 looking in the direction of the arrow and illustrating the other cutter of the double cutting mechanism.

30 Figure 6 is a horizontal sectional view through the throat of the machine frame and related parts, illustrating the manner of applying and tensioning a tie wire to position end portions of a looped wire in side by side or parallel relation prior to the operation of joining said end portions by a splice or knot usually produced thereon by twisting said end portions.

35 Figure 7 is a detail view of the knot or splice produced on the tie wire by the operation of the twisting mechanism embodied in the machine, illustrating the cut extremities of the wire and their compact disposition with reference to the looped wire and the knot or splice.

40 As shown, the machine frame A is a simple casting embodying a base plate a with up-standing shaft bearings a' which provide a plurality of parallel members a^2 . At the front part of the frame a slot or throat b is formed in the members a^2 , and the front edge of said base plate is inclined at b' , the inclination or slope b' being downwardly with respect to the slot or throat b . At the rear part of the base plate is a raised flange b^2 acting as a stop and rest for the tension lever C and the twister-operating lever D.

45 E, F, are wire retaining and shear members positioned against the outer faces of the parallel frame and members a^2 , said members E, F being shown in Figure 1, as positioned in recesses provided on the frame members a^2 . These shear members are composed of steel plates, fixedly attached to the frame members a^2 , and said shear members are provided with slots e, f which are in register or alignment with the throat b provided in the frame members a^2 , the outer ends of the slots e, f being open. The inclined or sloping face b' of the frame-base a , and the open ends of the slots e, f , permit the free introduction of the wire tie into the throat b when looping the same around a package.

The frame members a^2 are spaced as shown in Figure 6 to allow the use of twister supporting plates G, G' between them and to provide, also, for the introduction of the twister pinion H and the operating gear or segment I for said twister pinion. The plates G, G', shown in Figures 1, 2 and 6, are positioned laterally between the frame members a^2 and in contact with the inner faces thereof, said plates G, G' being fixedly secured to the respective frame members a^2 by any suitable means. Said plates G, G' are provided with openings serving as bearings for the journals or end portions of the twister pinion H, see Figure 6, and thus the twisting pinion is supported steadily in place for free rotation within the frame, by the provision of simple and efficient supporting means. The plates G, G' and the twister are readily removed when the twister becomes worn through use, so that a worn twister can be replaced by a new twister with facility. As is usual in this art, the twister is provided with a radial slot h , and said twister when at rest is positioned within the frame and between the plates G, G' for said slot h' to be in alignment with the throat b and the slots e, f , see Figure 6.

50 My machine embodies a single shaft J for the two levers C, D, and for the two tension heads K, L, thus simplifying the construction by reducing the number of parts. Said shaft is journaled in openings of the frame members a' , the opposite ends of said shaft extending for considerable distances beyond the bearings provided in said frame members a' in order to receive on said protruding ends of the shaft the rotatable heads K, L of the tensioning mechanism. Said heads K, L are attached fixedly to the shaft J by appropriate means, whereas the tension lever C and the twister lever D are sleeved loosely on the shaft, see Figure 2, whereby the shaft constitutes the axes of motion of the two levers and it carries the two tension heads K, L. As shown, the tension lever is provided with a hub or sleeve c offset from one end with respect to the axial line of the lever arm, see Figure 2, said sleeve being fitted loosely on the shaft J for contact with the frame member a' . The other lever D is provided or made unitary with the gear segment I and provided with a hub or sleeve d , the latter being fitted loosely on shaft J between adjacent frame members a', a' , see Figure 2, and thus the two levers C, D are mounted loosely on the shaft to swing or turn thereon when operated by hand.

55 The tension head K shown in Figures 1 and 2 is provided on one face with a ratchet k , i. e. 125 that face of the head which is next to the sleeve c of tension lever C has formed thereon a series of teeth constituting the ratchet k , and with said ratchet co-operates two pawls O, P, the former being carried by the lever C 130

and acting as a feed pawl to impart a rotative step motion to the head K, whereas the latter pawl P is mounted in a frame member a' and acts to restrain backward rotation of the head K under the pull or strain of the 5 looped wire when tension is placed thereon, said pawls O P being shown in Figure 2. The sleeve formed part c of lever C is provided with a pocket o within which is loosely fitted the plunger constituting the feed pawl, and this pocket houses a spring O', the latter 10 acting to impel the operative face or end of the pawl plunger into contact with the face of the ratchet k so as to coact with any one 15 of the teeth of said ratchet.

The check pawl P is a plunger shaped piece which is partly housed within a pocket p provided in one of the frame members a' , said pawl P being under the influence of a spring 20 P' which acts on the pawl to impel its exposed active end into contact with the ratchet k of tension head K, said pawl P being so fashioned and engaging in such manner with the ratchet that the pawl P permits the ratchet 25 to turn freely in one direction when the tension lever C is moved or swung in one direction, whereas said pawl P holds the ratchet k and head K from turning in an opposite direction under the pull of the tie 30 wire after the latter shall have been placed under tension. The check pawl P acts, also, to preclude the head K from rotative movement with lever C when the latter is returned to a normal position, in which it rests on the 35 ledge b^2 .

Said tension head K is shown as being constructed for use with wire in "cut lengths," i. e. wire straightened and cut to one length or the other according to the dimensions of 40 the package on which it is used. Two kinds of such cut length wire are now on the market, i. e. plain round wire cut to appropriate length, and shouldered wire composed of straightened pieces of determined length and deformed as in the Cary Patent No. 1,419,110, 45 June 6, 1922. Said head K is provided with a circumferential groove k' and a series of radial pockets k^2 , into either of which may be thrust one end of a piece of plain round 50 wire or the plain end of a round wire deformed at one end of the character disclosed in said patent. In addition to the groove k' and the pockets k^2 , the head K is provided on the face other than the ratchet face k , with a plurality of radial recesses m' forming a series of offstanding abutments m , see 55 Figure 1, and in the body portion of the head K is mounted a series of rotatable members M in the form of cylindrical pins, each 60 member being provided at the outer end with a recess m^2 which produces a holding shoulder m^3 on the pin. This shoulder m^3 is in facing relation to an abutment m' , and when 65 a deformed wire is used, the deformed end is 70 thrust into the space bounded by the abut- 75 ment m and the shoulder m^3 , whereupon the head K is rotated by hand so that the member M is rotated for the shoulder m^3 and the abutment m to engage with the shoulder on the deformed end of the wire, whereby the 70 tie wire is received and engaged by the head K so as to be held from slipping relatively to the head when tension is placed on the wire. The tension head K forms the subject-matter of a separate application filed by me 75 on October 3, 1924, Serial No. 741,514, and no further description thereof is required or necessary.

The double cutter mechanism includes two cutters or knives Q R, the former being positioned in shearing relation to the member E, and the latter being arranged in similar relation to the member F. Said cutter Q is mounted on one of the frame members a^2 by means of a pivot q so that it stands vertically 80 alongside of the member E, said cutter having a cutting edge q' and a depending shoulder q^2 , see Figure 4. The cutter Q is arranged for the cutting edge to move across the slot e in shear plate E, whereby the cutter Q is 85 in shearing relation to the said shear plate E. Said cutter is held in position by a concealed spring Q' housed within a pocket q^4 of the frame member, as shown in Figure 4, 90 said cutter being retained in position for the cutting edge q' to lie usually above the slot e to allow for the free introduction of the tie wire below said edge q' . The cutter Q severs one of the two parallel parts of the wire, 95 whereas the other cutter R severs the other 100 of said parallel parts of the wire, and to this end, said cutter R differs in construction from the cutter Q in the particulars shown in Figure 5, i. e. said cutter R is provided in its bottom edge with a notch r and is provided with a cutting edge r' . Similarly to cutter Q, the cutter R is positioned vertically alongside one of the shear plates, in this instance the shear plate F, it is pivoted by a pin r^2 to the 105 frame member a^2 , and its lower edge is furnished with a depending shoulder r^3 , the latter being engaged by a concealed spring R' housed within a pocket r^4 of the frame member a^2 , and as depicted in Figure 5. The notched lower edge r of the cutter R enables 110 it to straddle that strand or length of the parallel wires which, at the other end of the resulting knot or splice, is adapted to be cut by the edge q' of cutter Q, whereas the edge r' of said cutter R operates to sever the other 115 strand or length of said parallel wires, as a result of which the looped tie wire remains intact around the package. The cutters Q R are actuated on the forward swing 120 of the twister lever, the latter imparting rotative movement to the gear segment I for rotating the twister H in a manner to intertwist the parallel strands of the looped tie wire, but the actuation of the cutters is timed 125 with respect to the twisting of the parallel 130

strands of the looped tie wire so that the cutters sever the respective strands of the tie wire subsequently to the twisting of the looped tie. As shown, in Figure 2, lever D is provided with an enlarged integral member S near one end of the gear segment I, and from the member S projects the studs s s', one of which contacts with an edge portion of cutter Q and the other contacts with an edge of the cutter R, see dotted lines in Figures 4 and 5, upon the forward swing of the lever D. The cutters are operated successively on said forward swing of lever D by reason of the provision in cutter R of the notch r⁶, and thus the stud s acts on cutter Q a little in advance of the action of the stud s' on cutter R, although both cutters are operated by the lever D when it is moved forwardly to first rotate the twister and thereafter to actuate the cutters successively. The springs Q' R' hold the cutters Q R in the path of the studs s s', so that the two cutters are yieldable to the pressure of said studs, and both cutters are thus normally out of the way of the tie wire when looping the same around the package, the movement of the cutters in one direction being arrested by contact with the frame members a'. The member S of the twister lever carries means for taking up the shock of the lever when it is swung forcibly in one direction for operating the twister and is pressed forcibly downward to actuate the cutters Q R in severing the two strands of the looped wire. Said member S carries a plurality of plungers S', one on each side of the gear segment I, said plungers being fitted slidably in transverse pockets t provided on the member R. Each plunger is encircled by a concealed spring S² housed within one pocket t, and at one end each plunger is provided with an exposed contact piece t' and at the other end with a retaining pin t². As the lever D is swung forward to rotate the gear segment I and twister H, the plungers S' rest upon the upper faces of the frame members a², and when the operator applies force downwardly upon the lever D to actuate the cutters Q R for severing the wire, the twister is turned a certain angular distance, to complete the twisting operation and the plungers S' S' are yieldably forced by sliding in the pockets t and compressing the springs S², with the result that the first period in the travel of the lever D is cushioned by the springs S². Now when pressure on the lever D is relaxed, the recoil of the springs S² lifts the lever D a certain distance and this turns the segment I and twister H a corresponding distance with a view to bringing the slot in the twister into alignment with the throat b and slots e, f, and at the same time the notched edge r⁶ of cutter R clears the stud s' so that the spring R' acts on the cutter R to return it to position in which the notched edge r r' of said cutter R is

clear from the wire, it being apparent that the two springs Q' R' return the cutters eventually to their normal positions upon the backward swing of the twisting lever.

The frame members a' at the front part of the frame are notched at u to receive the direction rolls U, one at each side of the throat b and the slotted shear plates E F. These rolls are mounted for free rotation within the notched frame members, and these are positioned in the horizontal plane of the slot or throat b, and between said throat and the rotatable tension heads, said rolls functioning as a means for directing the tie wire and for minimizing the friction on said wire during the operation of tensioning the same.

The operation may be described briefly as follows: The machine is placed in any desired position upon a package, as in Figure 1, with the levers C D turned rearwardly and resting upon the ledge b². If a plain round wire tie is used, one end is thrust into a pocket h' and the head K turned by hand in a forward direction so as to bring the wire tie into position to bend it around a roll U. Assuming a shouldered wire is used, the deformed end is thrust between an abutment m and one member M, whereupon the head K is rotated to bring the wire into position to be bent around the roll U, and in this operation of turning the head K the pressure of the wire on the member M turns the latter so that the shoulder m³ of the member M and the abutment m of the head coat in engaging with the shoulders on the respective sides of the deformed wire in a manner to retain said wire against slipping when tension is placed on the wire.

One end of the tie wire having been initially attached to the head K, the operator proceeds to bend the wire around the left hand roll U, and to lead the wire through slot e, throat b, and slot f, of the machine, after which the wire is looped around the package as in Figures 1 and 6, and thereafter the free part of the wire is again positioned in the slot e, throat b, and slot f, and is bent around the other roll U and finally the extremity is partly wrapped around head L and bent into one of the slots l' thereof.

The wire is now looped around the package, its two ends are attached to the heads K L and two strands of the wire are positioned in substantially parallel relation within the slot e, throat b, and slot f, see Figure 6, so that the plates E F will hold said strands during the twisting operation, and one strand of the wire crosses the other strand at the right hand roll U, see Figure 6. The operator now presses downward the lever D for holding the machine steadily in place, and at the same time pulls upwardly the lever C to swing it forwardly. This motion of lever C is communicated by feed pawl O, in engagement with a tooth of ratchet k, to head K, and the latter

being fast with shaft J, in turn rotates shaft J and head L concurrently with the rotative movement of head K, whereby the two heads K L are rotated together through a certain angular distance. The heads K L thus pull on the wire to tension it by straining the wire equally, the wire being pulled in opposite directions, and the strain or pull tending to draw into the slot e, throat b, and slot f. The forward motion of the lever C thus rotates the two heads to apply tension to the wire, and the degree of this tension is within the skill and judgment of the operator, so that any desired tension can be placed on the wire, even to the extent of straining said wire to the breaking point, although the operator will, of course, apply such tension as will insure the wire being embedded in the corners of the package. At this stage, the check pawl F restrains the head K from turning in a reverse direction under the pull of the wire around the package, and it is due to this restraining influence of the pawl P co-operating with the ratchet k that the two heads and the shaft J will not slacken tension on the wire. The operator now reverses the tension lever while the check pawl F is acting on the ratchet, so that the lever C is returned to a position to rest upon the ledge b², and then the operator presses with one hand down on the lever C for holding the machine steadily in place, while with the other hand the operator pulls in an upward and forward direction on lever D, the effect of which is to turn the gear segment I and twister H for twisting together the substantially parallel strands of wire confined at the time in the slots e f and throat b. As the twister completes the twisting operation, the studs s s' press the cutters Q R for the cutting edges q' r' to sever the respective strands of wire and thus cut the surplus wire from the loop, the effect of which is to sever the two parts of the wire connected respectively to the heads K L and to release the machine from an anchored relation to the tied loop. As the lever D is pressed forcibly downward to sever the two wires, the springs of plungers S' are compressed to cushion the lever at the final stage of its movement, but when the pressure is relaxed, lever D is returned by the springs S² to a position wherein the twister H is returned to a position for the slot to align with slots e f and throat b, and the studs s s' are practically free from the cutters Q R which are returned by their springs to normal positions, whereby the edges q' r' are free from contact with the wire, said cutters operating to sever the wire at points close to the ends of the splice or knot and the twister having acted to turn the wire ends as shown in Figure 7, wherein said ends are disposed in compact relation to the loop wire so that there are no protruding ends to catch and injure the hands of the workmen who may be called upon to handle the tied

package. The machine is now shoved back away from the knot or splice, the wire being free to pass out of the throat b and slots e f.

The operations of looping the wire, placing tension thereon to the required extent, twisting the wire, and severing the wire are performed easily and quickly by unskilled operatives, the machine being semi-automatic in respect to the operation of its working parts.

Having thus fully described the invention, what I claim as new and desire to secure by Letters Patent is:

1. A wire tying machine embodying a shaft, a plurality of tension heads rotatable therewith, a tension lever, means operated by the lever for imparting a rotative motion to the shaft and the heads, and splice forming means for joining a looped band while said band is under tension by the action of said heads.

2. A wire tying machine embodying a plurality of rotatable tension heads each having means for the attachment of a wire loop thereto, a tension lever, clutch means operated by the lever for imparting a rotative movement to said heads, and splice-forming means operable upon the wire loop under tension.

3. A wire tying machine embodying a plurality of rotatable heads each having means for the attachment of a wire loop thereto, a shaft connecting said heads, a tension lever, clutch means operated by the lever for imparting a conjoint rotative movement to said heads, and splice-forming means operable upon the wire loop.

4. A wire tying machine embodying a wire receiving throat, a shaft at one side of said throat, a plurality of heads on said shaft, said heads being provided with means for the attachment thereto of a wire loop, a tension lever, clutch means operated by the lever for imparting a conjoint rotative movement to the shaft and said heads, and splice-forming means operable on the wire loop.

5. A wire tying machine embodying a shaft, a plurality of tension heads one of which is fast with said shaft and the other of which heads is loose on the shaft for rotation in one direction relatively thereto, said heads being provided with means for the attachment of a looped wire tie and said loosely mounted head being rotatable at will upon the initial attachment of said wire tie, a tension lever, clutch means operated by said lever for imparting conjoint rotative movement to the shaft and said heads, and splice-forming means for lapping portions of said wire loop.

6. A wire tying machine embodying a shaft, a plurality of tension members one of which is free on the shaft and is operable at will upon the initial attachment of a wire tie, a tension lever, clutch means operable by said lever whereby the movement of said tension

lever is communicated to said tension members for imparting concurrent movement thereto for straining the loop of a wire tie by pulling the same in opposite directions, 5 and splice-forming means operable independently of said tension lever for uniting the wire tie to produce a closed loop.

7. A wire tying machine embodying a shaft, a plurality of tension heads each having means for the attachment of a looped wire tie, a tension lever, clutch connections intermediate said lever and said shaft whereby the motion of the lever is communicated through one of which heads to the shaft and 10 the tension heads are rotated concurrently with the shaft for straining the looped wire tie by pulling in opposite directions thereon, and splice-forming means for uniting the wire tie to produce a closed loop.

15 8. A wire tying machine embodying a shaft, a plurality of tension heads each having means for the attachment of a looped wire tie, a tension lever, one of said heads provided with a ratchet, a tension lever, a 20 feed pawl carried by said lever and engaging said ratchet for imparting rotative movement to said head and through the shaft for imparting rotative movement to the other head, and splice-forming means operable at 25 will for joining the wire tie to produce a closed loop.

9. A wire tying machine embodying a shaft, a tension head provided with a ratchet, a lever loose on the shaft, a feed pawl carried by the lever and co-operable with the ratchet, a second tension head fast with the shaft, said two named tension heads operating to pull in opposite directions upon a 30 looped wire tie, and splice-forming means 35 operable at will for joining the wire tie to produce a closed loop.

10. A wire tying machine embodying a shaft, a tension head provided with a ratchet.

a lever loose on the shaft, a feed pawl carried by the lever and co-operable with the ratchet, a second tension head fast with the shaft, said two named tension heads being rotatable conjointly and operating to pull in opposite directions upon a looped wire tie, 45 a check pawl co-operating with the ratchet for restraining rotative movement of said two tension heads under the strain of an applied looped wire tie, and splice-forming 50 means operable at will for joining a wire tie into a closed loop.

11. In a wire tying machine embodying a throat for receiving side by side portions of a wire tie when formed into a loop, a shaft, a plurality of tension members each having means for the attachment of a wire tie, a lever for operating said shaft and tension members for imparting conjoint rotative movement thereto, tie directing means positioned for determining the path of the wire tie when looping the same, and splice-forming 55 means for joining the wire tie to produce a closed loop.

12. A wire tying machine embodying a throat for receiving side by side portions of a wire tie when formed into a loop, a shaft, 60 a plurality of tension members each having means for the attachment of a wire tie, a lever for operating said shaft and rotating the tension members concurrently for pulling in opposite directions on the looped 65 wire tie, tie directing means intermediate the tension members and said throat whereby the movement of the tension members draws the side by side portions of a wire tie laterally into the throat, and splice-forming 70 means operable at will for joining the side by side portions of the wire tie to produce a closed loop.

In testimony whereof I have hereto signed my name this 23 day of October 1924.

JOHN SHERMAN McCHESENEY.
